US00D950236S

(12) **United States Design Patent** (10) Patent No.: **US D950,236 S**
(45) Date of Patent: ** May 3, 2022

(54) **ACCESSORY FOR AN ELECTRONIC DEVICE**

- (71) Applicant: **Apple Inc.**, Cupertino, CA (US)
- (72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)
- (73) Assignee: **Apple Inc.**, Cupertino, CA (US)
- (**) Term: **15 Years**
- (21) Appl. No.: **29/739,577**
- (22) Filed: **Jun. 26, 2020**
- (51) LOC (13) Cl. **03-01**
- (52) U.S. Cl. **USPC D3/215; D3/207**

(57) **CLAIM**

The ornamental design for an accessory for an electronic device, as shown and described.

DESCRIPTION

FIG. 1 is a bottom front perspective view of an accessory for an electronic device showing the claimed design; FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a perspective view thereof showing an accessory for an electronic device in an environment in which it may be used.

The broken line showing of a portion of the accessory for an electronic device in FIG. 9 is included for illustrating environmental structure and forms no part of the claimed design.

1 Claim, 4 Drawing Sheets
